ILLUMINATED DEVICE

Filed June 8, 1938

UNITED STATES PATENT OFFICE

2,240,608

ILLUMINATED DEVICE

Zigman Chaplick, Chicago, Ill.

Application June 8, 1938, Serial No. 212,506

5 Claims. (Cl. 240—81)

My invention relates to illuminated devices such as smoking stands. It relates more in particular to an improvement wherein a night lamp or the like may be disposed between the head and base of the stand, and wherein the illuminating lamp is readily replaceable without dismantling the smoking stand, or the like, in any way.

While my invention may be employed with many different types of articles where illumination is desired, I have shown it and shall describe it primarily as embodied in a smoking stand. Smoking stands are usually equipped with a base, a vertical upright of suitable design carried usually substantially centrally of the base, and a head or tray near the top of the upright carrying smoker's articles such as ash receivers, receptacles for cigars, cigarettes and tobacco, a lighter and the like. It has been suggested in the past that smoking stands be equipped with night lamps, preferably lighted with a relatively small bulb, and shaded with a translucent glass so as to have a decorative as well as a utility function. It has been suggested that the night lamp be carried at or near the base in order that the small electric bulb employed may be readily removed by picking up the stand and grasping the lamp under the base which is arranged for ready access to the lamp. There are many objections to having a stand article such as a smoking stand carry a night lamp in this position as those skilled in the art understand. However, heretofore, particularly with conventional structures which have been used in recent years, it has been impossible to satisfactorily equip a smoking stand or similar article with a night lamp provided in any other suitable location. The principal difficulty has been due to the inaccessibility of the lamp when and if a substantially uniform and conventional type of design and structure is utilized.

The principal object of my invention is the provision of an improved stand article of the smoking stand type.

Another object is the provision of a night lamp disposed between the base and head and arranged for easy accessibility of the lamp without impairing design features.

Another object is to embody a night lamp or decorative type of lamp in a stand article in such a way as not to affect the symmetry or beauty of design which may be built into such articles, while still maintaining ready accessibility of the lamp when changes are necessary.

Other specific objects and features of my in-

vention will be apparent from the detailed description which follows.

In the drawing

Fig. 1 is a side view partly in section and partly in elevation showing a preferred embodiment of my invention;

Fig. 2 is an enlarged exploded view partly in section showing some of the principal parts concerned with the embodiment of the invention disclosed in Fig. 1;

Fig. 3 is an enlarged fragmentary sectional view partly in elevation illustrating a feature which may be employed;

Fig. 4 is an enlarged fragmentary perspective view partly in section illustrating the manner in which the translucent lamp housing is mounted into position, and

Fig. 5 is a fragmentary elevational view showing the parts in their normal position.

The general structural features of the main portion of the device of my invention follow a practice which, by virtue of many years experience, has been found to be satisfactory from both a manufacturing and use standpoint. I modify this construction, however, in so far as the present invention is concerned, to permit the use of the standard structure while still avoiding disadvantages deemed to be inherent in such structure where the provision of a suitable lamp intermediate the base and head was desired.

Looking at the drawing, I utilize a base 10, central support 11 and tray or head 12, while nested between the base and head are decorative design members held together and around the central support 11 by pressure between the head and base. A handle 13 is threaded to the top of the support so as to hold the head or tray 12 in position, and at the bottom of the support the base 10 is also mounted on similar threads.

Immediately above the base is a centrally disposed style ring 14, together with other decorative members which need not be referred to here in detail as they may be modified and form no essential part of the present invention except as will be pointed out hereinafter.

Above the base I provide a translucent housing member 16 and above this member and spaced therefrom is a complementary translucent housing 17. The translucent housing 16 is provided with an annular upper recessed portion over which a ring 18 engages snugly. This ring 18 carries a plurality of lugs 19, 21, and 22 projecting upwardly and slightly inwardly and so finished at their tops that the upper surface of the lugs together lie in a horizontal plane. The lugs,

in effect, comprise sections of a cylinder so that they engage the lower edge of the translucent housing 17. It will be seen that the decorative members surrounding the central support 11 engage against a ring 23 disposed to engage in a recess 24 at the upper part of the translucent housing 17, and a decorative member 26 engages the bottom plane surface of the housing 16 and also partly around the outside periphery thereof as appears clear from Figs. 1 and 5. The result of this construction is that the two housing members are supported firmly in position on the central upright but spaced from each other a distance equal to the height of the lugs 19, 21, and 22. Thus, a rigid structure is provided such as is absolutely necessary in stand articles of this general character.

The lug 22 is provided with a projection 27 to which a lamp socket 28 is connected by suitable means such as a screw 29. This socket 28 is adapted to receive a small lamp 31 of such a size as to provide a gentle or mild illumination such as may be used for night light purposes.

Since the translucent housing members 16 and 17 are spaced from each other, and since the lugs which hold them apart are spaced in the manner shown, the lamp is easily removed from between the two housing members. To cover the lugs and the lamp, I provide a closure ring 32 and a lug 33 which, when the ring is placed in position and given a partial rotation, engages under the projection 27 on the lug 22.

Any suitable switch means may, of course, be employed for delivering electric current to the lamp 31. I show a conveniently placed foot switch 34 mounted on the base, which is included in the circuit supplying current to the lamp 31. A suitable cord 36 is adapted to be plugged into a usual base board or similar outlet for supplying the necessary power. The current may also be delivered to an electric lighter 37 placed on the head or tray 12, and controlled by a suitable switch 38 which can be operated by the thumb or finger.

It will be seen from Fig. 5, taken with Fig. 1 which completes the design, that the smoker shown may be designed to have symmetrical outlines, a pleasing appearance and to embody all of the usual features common to stand articles of this type. When the lamp is lighted by operation of the switch 34, the translucent housings 16 and 17 glow, producing a decorative effect and providing adequate illumination for night light purposes. There is no shadow cast by the central support, and the closure ring 32 does not in any sense mar the appearance of the illuminated portion nor impair its efficiency for night light purposes. Should it be necessary to replace the lamp 31, all that is necessary is to give the closure ring 32 a partial rotation in a counter-clockwise direction, lift it sufficiently to uncover the opening between the lugs 19, 21 and 22, and proceed to make the necessary change in lamps. In this connection, it may be noted that lamps for different purposes may be provided in different colors, and the user of the article may wish to change from one color to another for purely aesthetic reasons, that is, he may wish to change lamps even though the lamp provided with the article has not burned out.

My invention is obviously capable of modification while still utilizing the essential novelty of the invention as defined in the appended claims. For example, because of requirements of changed design, or for other reasons, modified structures

may be provided without departing from the scope of my invention. The invention clearly may be employed on such articles as table lamps, floor lamps, torchieres, and the like where it is desirable to provide a lamp of the general character described between the base and top of a generally vertical support.

What I claim as new and desire to protect by Letters Patent of the United States is:

10 1. In a smoking stand or the like, a central support, a two-part translucent housing surrounding said support, spacing means between said housing members, said spacing means having an opening therein, means for holding said housing members and spacing means in intimate relation, a lamp disposed between the housing members and near said opening, and a ring member substantially coextensive in height with the space between the housing members, said ring

15 normally supported to close said opening, but adapted to be raised to uncover said opening, said housing members serving as a shade for said lamp, substantially the entire surface of which is illuminated thereby.

20 2. In a smoking stand or the like, a central support, a lower translucent housing member surrounding said support, a ring disposed above said housing member and having a plurality of upwardly extending lugs, an upper translucent housing member surrounding said support and having a lower edge resting on said lugs, a lamp carried by one of said lugs, and means disposed between said housing members for concealing said lugs and closing openings between them, said housing members serving as a shade for said lamp, substantially the entire surface of which is illuminated thereby.

25 3. In a smoking stand or the like, a central support, a lower translucent housing member surrounding said support, a ring disposed above said housing member and having a plurality of upwardly extending lugs, an upper translucent housing member surrounding said support and having a lower edge resting on said lugs, a lamp carried by one of said lugs, and a ring having substantially the height of said lugs and normally resting on said first-mentioned ring, said second-mentioned ring being removable to permit access to said lamp, said housing members serving as a shade for said lamp, substantially the entire surface of which is illuminated thereby.

30 4. In a smoking stand or the like, a base, a hollow member extending upwardly therefrom and through which an electrical conduit is adapted to pass, an enclosure housing a source of electric illumination, said enclosure being disposed above said base and comprising spaced upper and lower light translucent parts, a ring associated with said lower part, said ring being provided with upstanding members one of which serves to support an electric socket within which a bulb may be mounted, and all of which serve to space the light translucent parts of the housing, and a ring member associated with said upper part of the enclosure, said last-mentioned ring member serving to substantially close the space between the said upper and lower light translucent parts of the enclosure and being readily removable upwardly whereby to provide easy access to said electric light socket.

35 5. In a smoking stand or the like, a generally rod-like support member, a pair of translucent housing members extending around the support member intermediate the ends thereof, said housing members shaped to define together a

lamp enclosure, a ring engaging one housing member and having a plurality of lugs engaging the other housing member, a lamp socket mounted within the said lamp enclosure in a position to permit insertion of a lamp through an opening between said lugs, ring means releasably

disposed between the housing members and over said lugs, and means for supporting said housing members against longitudinal movement along said support.

5

ZIGMAN CHAPLICK.
